Ernest Nunes

UNITED STATES PATENT OFFICE

130,389

DESIGN FOR A YACHT HULL

Ernest Nunes, Sausalito, Calif.

Application April 18, 1940, Serial No. 91,761

Term of patent 14 years

To all whom it may concern:

Be it known that I, Ernest Nunes, a citizen of the United States of America, residing in Sausalito, county of Marin, and State of California, have invented a new, original, and ornamental Design for a Yacht Hull, of which the following is a specification, reference being had to the accompanying drawing, forming a part thereof.

In the drawing:

Figure 4, a bow view.

I claim:

The ornamental design for a yacht hull, as shown.

ERNEST NUNES.
